UNITED STATES PATENT OFFICE.

CHIEF TWO MOON MERIDAS, OF WATERBURY, CONNECTICUT.

DESIGN FOR A RING.

Application filed June 11, 1925. Serial No. 13,739. Term of patent 14 years.

To all whom it may concern:

Be it known that I, CHIEF Two Moon MERIDAS, a citizen of the United States, residing at Waterbury, in the county of New Haven and State of Connecticut, have invented a certain new, original, and ornamental Design for Rings, of which the following is a specification.

Reference is had to the accompanying drawings forming part of this application in which:—

I claim:

The ornamental design for a ring, as shown.

Signed at Waterbury, Connecticut, this 6th day of June, 1925.

CHIEF TWO MOON MERIDAS.
